INVENTOR,
George C. Van Keuren,
By Attorneys,

UNITED STATES PATENT OFFICE.

GEORGE C. VAN KEUREN, OF DUQUOIN, ILLINOIS.

PIPE-EXPANDER.

SPECIFICATION forming part of Letters Patent No. 381,094, dated April 10, 1888.

Application filed December 9, 1887. Serial No. 257,432. (No model.)

To all whom it may concern:

Be it known that I, GEORGE C. VAN KEUREN, a citizen of the United States of America, residing at Duquoin, in the county of Perry and State of Illinois, have invented certain new and useful Improvements in Flue-Expanders, of which the following is a specification, reference being had therein to the accompanying drawings.

10 This invention pertains to certain new and useful improvements in flue or tube expanders, having for its object the provision of a device simple in construction and combining durability and cheapness.

15 The invention is so constructed as to be applicable to two sizes of flues or tubes, whereby it is rendered doubly useful.

In the accompanying drawings, Figure 1 is a view in perspective of my invention. Fig. 20 2 is a side elevation. Fig. 3 is a sectional view thereof, and Fig. 4 is a detail view.

Referring to the drawings, A represents a circular plate or head, having a continuous projecting flange, *a*, as shown, and is provided 25 with a central circular opening, *a'*, and three (more or less) radiating slots, *a''*, extending from said central opening.

To the inner surface of the plate or head A are rigidly secured or formed integral there- 30 with three approximately V-shaped lugs or arms, *b b*, having their vertexes pointing toward the center of the central opening.

Within the radiating slots *a''* are disposed 35 rollers C, provided each with a circular groove, *b'*, for fitting within said slots, said rollers being held therein as against displacement when not in use by means of a wire ring, D, disposed in a groove in the wall of the central circular opening *a'*, the ends of said ring being unconnected.

40 E is a tapering mandrel of ordinary construction designed to be inserted through the central opening, *a'*, of the plate or head, so as to act on the rollers C.

45 From what has been said it will be seen that upon placing my flue-expander on the end of a tube or flue its circular flange *a* will encompass the outer surface of said tube or flue, and

by driving the tapering mandrel tightly between the rollers the latter will be moved in 50 their respective slots, and thus act upon the end of the flue or tube, causing the expansion thereof around the opening in the boiler-head, whereby it is securely held in position. It will also be seen that the lugs or arms guide 55 the rollers in their movement and prevent any deflection thereof from their proper positions; and by reason of the ends of said lugs or arms being unconnected, or openings left therein between, the rollers can move outwardly, and 60 thereby one device can be used to operate on two sizes of flues or tubes.

If desired, without departing from the spirit of my invention, the length of the circular flange *a* can be shortened or dispensed with, 65 so as to provide means for operating on flues having but a small projecting portion.

My improved flue or tube expander is extremely simple, cheap, and durable, and, as it comprises but few parts, is not liable to get 70 out of order or to become disarranged.

I claim as my invention—

1. In a flue-expander, the combination, with the plate or head having a central opening and radiating slots and a groove or recess, of 75 the rollers having their necks in said slots, the ring disposed in said groove or recess, having its ends disconnected, the V-shaped lugs or arms projecting from said plate or head, and the tapering mandrel designed to be inserted through said central opening and bear 80 against the said ring and rollers, substantially as shown and described.

2. The combination, with the plate or head having the central opening provided with a 85 circular groove and the radiating slots, of the rollers secured in slots, and the ring having its end disconnected and disposed in said groove for retaining said rollers in position, substantially as shown and described.

In testimony whereof I affix my signature in presence of two witnesses.

GEORGE C. VAN KEUREN.

Witnesses:

W. H. EAST,

L. S. SMITH.
